UNITED STATES PATENT OFFICE.

FRANK A. BURNHAM, OF CLEVELAND, OHIO, ASSIGNOR TO THE CHANDLER & PRICE COMPANY, OF SAME PLACE.

MOVABLE AND ADJUSTABLE BEARER FOR PLATEN PRINTING-PRESSES.

SPECIFICATION forming part of Letters Patent No. 595,991, dated December 21, 1897.

Application filed July 22, 1897. Serial No. 645,550. (No model.)

To all whom it may concern:

Be it known that I, FRANK A. BURNHAM, a citizen of the United States, residing at Cleveland, in the county of Cuyahoga and State 5 of Ohio, have invented certain new and useful Improvements in Movable and Adjustable Bearers for Platen Printing-Presses; and I do declare that the following is a full, clear, and exact description of the invention, 10 which will enable others skilled in the art to which it appertains to make and use the same.

My invention relates to platen printing-presses; and the invention consists in movable and adjustable bearers for the ink-rollers 15 and mechanism connected with the back shaft, whereby when for any reason the throw-off mechanism is operated to prevent an impression the said bearers will be carried forward, so as to prevent the ink-rollers from 20 inking the type-form, and whereby said bearers may be set or adjusted to regulate the depth of contact or relation of the ink-rollers to the type-form, all substantially as shown and described, and particularly pointed 25 out in the claims.

In the accompanying drawings, Figure 1 is a side elevation of a press containing my improved mechanism. Fig. 2 is a plan view of the press on line xx , Fig. 1. Fig. 3 is a cross-30 section on line 3 3, Fig. 2, showing the bearer-operating mechanism in impression and inking position, as in Fig. 1. Fig. 4 is a cross-section of Fig. 2 on line 3 3, the same as Fig. 3, but showing the bearer-operating mechanism as it appears when the impression is thrown off and the inking-rolls are out of contact. Fig. 5 is an enlarged elevation and section on line 3 3, Fig. 2, of the back shaft and my novel mechanism for setting the ink-40 rolls at a suitable working depth. Fig. 6 is a sectional plan view of said mechanism.

A represents the frame of the press, and B the bed thereof.

C is the back shaft, which extends laterally 45 through the bed and is adapted to be rotated to effect the operations hereinafter described.

D is the ink-roller frame.

E is the connecting-rod from the power-communicating disk F to the shaft C, and F' 50 is the main lever, by or through which the pressman throws the ink-rollers out of con-

tact with the type-form and the said form out of impression at the same operation. To these ends the lever F' is operatively connected with shaft C through two gear-segments G and H, supported on the side and foot of the press and meshed to be operated together. A crank-arm 2, rigid with segment G, and a link 3, connecting said arm with lever F', serves to operate said segment, and a 60 bar or rod or the like, K, connects segment H with a short arm 4, rigid with shaft C. Lever F' is suitably pivoted on frame A, with throw enough to easily and quickly operate segment G, and thence the shaft C, as the demands of the press may require. The shaft 65 C has thus imparted a rotary movement, and the connecting-rod E is supported thereon by a wrist-pin eccentric to the axis of the shaft, so that when said shaft is rotated the 70 impression throw-off is effected, as fully set forth in a concurrent application, Serial No. 645,551, in which the throw-off mechanism is claimed as a distinct and separate invention.

Referring now more especially to Fig. 2, we 75 see the mechanism for keeping the ink-rolls out of inking relation to the type-form, comprising two side bearer plates or parts L, alike in construction and function and having their front bearing edges or surfaces widened somewhat by lateral flanges, which overlap the fixed or stationary bearers 5 of the press. These plates extend rearward toward shaft 80 C in form substantially as seen in Fig. 5, where they are engaged by a transverse rod 85 N, which projects at its ends through slots 6 in the bed into said plates.

On shaft C are sleeved two corresponding hubs M, made rigid with said shaft by set-screws or any suitable means and having eccentric-bearings 8 on which ride the collars P, fitting closely on said bearings. These collars have each an inwardly-projecting portion with circular bearings 9, in which the rod N is supported through hubs R, fixed rigidly 90 on said rod and having each an eccentric portion 10, engaged in said bearings 9. Hence when shaft C is rotated the eccentrics 8 have throw enough to carry the rod N and bearer-plates L a sufficient distance to keep the ink-rollers S out of contact with the type-form T, and when rotated to the opposite position said 100

parts are of course restored again to working relation, as seen in Fig. 2. The difference of position effected through eccentrics 8 is shown in Figs. 3 and 4, Fig. 3 showing working position and Fig. 4 idle position.

Now as a further feature of invention I have devised means for fixing the working position of the ink-rollers. These rollers are liable to operate with varying effects, even when relatively under the same adjustment, owing to differences in the consistency or condition of the ink or of the roller itself, so as to require adjustment on that account, and then again rollers will gradually shrink during use and require adjustment for this reason. Therefore to provide for these contingencies I have fashioned the hubs R not only with the eccentric extensions 10, but with means to rotate said hubs in their bearings, consisting in a segmentally-slotted flange 12 on each of said hubs and a set-screw 14, engaged through the slot in said flange to fix the hub in any adjusted position. The rod N turns with the hubs R in the construction here shown, but this is not necessary. Thus the bearer-plates may be set or moved to any needed position independently of the operations of shaft C, but when once set the other operations are the same as if this special adjustment had not been made.

What I claim is—

1. The bed of the press and the bearer-plates supported movably at the sides thereof, a member engaging said plates, the back shaft and eccentric-bearings thereon and connections arranged to engage said member and operate said plates, substantially as described.

2. The bed of the press and the fixed bearers for the ink-rolls, movable bearer-plates extending in front of said fixed plates and mechanism to adjust said movable plates comprising eccentrics, substantially as described.

3. The bed of the press and the movable bearer-plates thereon, the transverse rod engaging said plates and eccentrics on said rod and bearings to set the plates in working position, substantially as described.

4. The back shaft and means to rotate the same, in combination with the bearer-plates and means to operate said plates comprising eccentrics on said shaft, a rod engaging said plates, and collars on said eccentrics constructed and arranged to engage said rod, substantially as described.

Witness my hand to the foregoing specification this 8th day of July, 1897.

FRANK A. BURNHAM.
